UNITED STATES PATENT OFFICE.

WILLIAM A. SMITH, OF DENVER, COLORADO, ASSIGNOR TO THE DENVER ROCK DRILL MANUFACTURING COMPANY, OF DENVER, COLORADO, A CORPORATION OF DELAWARE.

TOOL-RETAINER.

1,273,944.

Specification of Letters Patent. Patented July 30, 1918.

Application filed October 18, 1917. Serial No. 197,262.

To all whom it may concern:

Be it known that I, WILLIAM A. SMITH, a citizen of the United States, residing at Denver, in the county of Denver and State of Colorado, have invented certain new and useful Improvements in Tool-Retainers, of which the following is a specification.

The present invention relates to tool retainers, and is particularly intended for 10 that type used on rock drills to hold the drill steel in the holder during the removal of the steel from the drill hole.

The object is to provide a simple retainer that will not only effectively engage the drill 15 steel, but will be securely interlocked therewith upon the rearward movement of the drilling apparatus, thereby overcoming the tendency of the tool retainer to slip or snap out of its operative position.

20 The preferred embodiment of the invention is illustrated in the accompanying drawings, wherein:—

Figure 1 is a side elevation of the apparatus.

25 Fig. 2 is a plan view of the same.

Fig. 3 is a detail view on an enlarged scale, but showing the yoke without the drill steel therein.

30 Fig. 4 is a front end view of the tool holder and retainer.

Fig. 5 is a sectional view on the line 5—5 of Fig. 3.

35 Fig. 6 is a detail sectional view through one of the ears to illustrate the shape of the opening therethrough.

Fig. 7 is a detail sectional view indicating the manner in which the shank collar interlocks with the yoke.

40 Similar reference numerals designate corresponding parts in all the figures of the drawings.

In the embodiment disclosed, the tool holder is designated 8, and is preferably at the front end of the drilling apparatus, being 45 provided with ears 9, through which side bolts 10 pass that secure the holder in place on the apparatus. Springs 11 are located on these bolts 10, to provide a yielding mounting for the head or holder 8.

50 Said holder is also provided at its front end with oppositely extending ears 12 having their front faces formed of angularly disposed sections 13 and 14 and their rear faces also formed of angularly disposed sections 15 and 16, the face sections 13 being

parallel to the face sections 15, and the face sections 14 likewise being parallel to the face sections 16. Openings 17 are formed through the ears and taper to the centers thereof.

The tool retainer consists of a yoke 18 having a drill steel-embracing loop 19 with integral rearwardly extending arms 20. The rear portions 21 of these arms are parallel to each other and are slidably mounted in the openings 17 of the ears 12. Said arms 65 are provided with integral enlargements 22 forming stop abutments against which are placed washers 23, the said washers being adapted to bear against the face sections 13 and 14 accordingly as the yoke is swung 70 to an inoperative or an operative position with respect to the tool to be retained. The rear ends of the arms are threaded to receive nuts 24, and washers 25 are located thereon and are arranged to bear against the rear 75 face sections 15 and 16 accordingly as the yoke is swung. Springs 26 interposed between the nuts 24 and washers 25 serve to yieldingly hold the yoke in its rearmost position with the washers 23 abutted against 80 the front faces of the ears 12.

The drill steel to be retained may be of any desired or well known construction. In the embodiment disclosed a portion of such a steel is shown at 27, and is provided with 85 a collar 28 that has too great a diameter to pass through the loop 19 of the tool retainer.

With swinging retainers of this general type, there is a possibility of the retainer 90 swinging from its operative position, as shown in full lines in Fig. 1, to its inoperative position, as indicated in dotted lines when strain is brought against the same. To prevent this in the present embodiment, the 95 rear side of the steel-embracing loop 19 is provided with a curved flange 29, the ends of which are shown at 30. This flange provides a socket 31 at the rear side of the loop 19, said socket being of sufficient diameter to loosely receive the collar 28. The ends 30 of the flange or socket wall are spaced apart a distance sufficient to permit the passage of the drill steel shank, but the distance between said ends 30 is less than 100 the diameter of the collar 28.

With this construction, it will be evident that when the drill steel is in the position shown in Figs. 1 and 2, the retainer may be 110 swung freely between an inoperative and

- an operative position with respect to said steel. If, however, the drilling apparatus is moved rearwardly for the purpose of extracting the tool, the collar will enter the socket 31, and consequently the drill steel and yoke will be interlocked, so that the latter cannot accidentally swing to an inoperative position by reason of the force exerted thereagainst.
- 10 From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.
- 15 Having thus fully described my invention, what I claim as new, and desire to secure by Letters Patent, is:—
1. In apparatus of the character set forth, the combination with a tool holder, of a swinging tool retainer movable into and out of a position to engage a tool to prevent detachment of the same from the holder, said retainer having means that detachably and automatically interlocks with the tool on the rearward movement of the tool retainer with respect to the tool to prevent the swinging movement of the retainer to an inoperative position.
2. In apparatus of the character set forth, the combination with a tool holder, of a swinging tool retainer movable into and out of a position to engage a tool to prevent detachment of the same from the holder, said retainer having means that detachably and automatically interlocks with the tool on the rearward movement of the tool retainer with respect to the tool to prevent the swinging
- 20 movement of the retainer to an inoperative position, said means automatically disengaging the tool when the tool retainer is moved forwardly with respect to the tool to permit the swinging movement of the retainer to an inoperative position.
- 25 3. In apparatus of the character set forth, the combination with a tool holder, of a swinging tool retaining yoke having a drill shank-embracing loop and provided with spaced stops at its rear side, the space between said stops being greater than the diameter of the drill shank and less than that of the drill shank collar.
- 30 4. In apparatus of the character set forth, the combination with a tool holder, of a swinging tool retaining yoke having a drill shank-embracing loop and provided with a drill shank collar receiving socket in its rear side, said socket having an open side that is narrower than the diameter of the drill shank collar.
- 35 5. In apparatus of the character set forth, the combination with a tool holder having a socket and spaced ears projecting on opposite sides of the socket, of a swinging tool retaining yoke having a drill shank-embracing loop and side arms that are slidably mounted in the ears, springs for yieldingly resisting the forward movement of the arms with respect to the tool holder, and a drill shank-collar receiving socket in the rear side of the loop, said socket having an open side that is narrower than the diameter of the collar of a drill shank placed in the tool holder.

In testimony whereof, I affix my signature in the presence of two witnesses.

WILLIAM A. SMITH.
